METHOD OF DESTROYING INSECTS AND
MICROORGANISMS

Ivar Rennerfelt, Djursholm, Sweden

No Drawing. Application September 1, 1934, Serial No. 742,449. In Sweden September 4, 1933

5 Claims. (Cl. 43—124)

The present invention has for its objects to provide an efficient, cheap and harmless method for killing all kinds of vermin such as lice, fleas, moths, cockroaches, ants, etc., and microorganisms such as bacilli and bacteria in all kinds of localities such as living rooms, schoolrooms, assembly halls, hospitals, soldiers barracks, kitchens, magazines, passenger cars and other public vehicles, stables, etc.

10 The method consists principally in raising the temperature in the space to be treated to such a degree, that the vermin and microorganisms can not survive the serious changes in their physiological conditions, which take place at a temperature between 40° and 45° C. as far as the insects are concerned, whereas the microorganisms perish at a temperature ranging from 45° C. to about 65° C. and in a few cases somewhat higher.

20 In order to quickly raise the temperature sufficiently a powerful source of heat is temporarily introduced into the space and caused to produce heat at a controllable rate of speed and is placed at a nearly central place in the room. Preferably an oil burner or an appliance for burning a gaseous fuel may be used in the form of an easily transportable stove capable of causing a complete combustion of the fuel. It is, naturally, possible to use also an electric heating appliance 30 in cases, where cheap and sufficient electric power is available but ordinarily heavy oil such as is used in central heating systems will be found convenient, cheap and not liable to cause any fire hazards.

35 The locality to be treated, especially if it is a living room, should be well closed to prevent the vermin from escaping into adjacent rooms, which is likely to happen as practical trials with the new method have indicated. The vermin quickly appear on the walls and furniture as soon as the temperature begins to rise above normal values and become more and more lively up to about 35° C., when the insects appear to become alarmed and try to find some means of escaping the unusual physical conditions. Consequently the room under treatment must be well closed, which means that certain steps are required to keep the burner in proper action without causing smoke and soot to spread in the room.

40 It is obvious that the amount of oxygen required to keep the burner in proper condition for a perfect combustion will gradually become exhausted, being partly replaced by carbon dioxide and steam, the atmosphere in the space becoming composed of a hot mixture of said gases and

5 nitrogen and, thus, very unsuitable for keeping the physical activities of insects and bacilli in normal condition. The peculiar method of causing said disinfecting and disinsecting condition of the atmosphere makes it necessary to provide not only an efficient stirring action in the gases for distributing the heat uniformly all over the room, thus, avoiding overheating furniture and other objects liable to become damaged on being exposed to an uneven rise of the temperature but also a constant supply of fresh air for the maintenance of complete combustion. A sufficient stirring may be caused by providing a circulating fan close to the stream of hot combustion gases, which may by this means become deviated in any desired direction, preferably downwards in order to cause a more rapid heating, especially of the lower parts, for instance, the floor and carpets, etc., on the floor. If such deviation of hot gases produced in the combustion zone is not provided, it is obvious, that they will rise immediately to the ceiling causing not only a very uneven distribution of the heat but also some danger of very serious damage to the upper parts of the room.

25 The same is true in case the heat is being produced by means of an electric heating appliance, which, thus, should be combined with means for efficiently circulating the heated air downwards to the floor and wall surfaces, avoiding over-heating of the ceiling above the place, where the heat is being produced.

30 The circulation of the atmosphere is conveniently obtained by installing an electric motor for running the fan, which may be placed vertically or horizontally or in an inclined position as demanded by the circumstances in each case. To prevent overheating the windings of the motor should be dustproof and so enclosed that cool air may be caused to flow through the windings. 35 The motor may be provided with a flexible hose connected to the outside of the house or with adjacent rooms and may be caused to draw the required air by means of a circulating fan or by a special suction fan. It is, thus, possible to let the air required for cooling purposes pass on into the zone of combustion, from where the surplus air may escape together with the steam and CO₂ in case all the oxygen is not consumed. A convenient method of supplying the fresh air required is to pass a hose or tube out through a narrow opening in a slightly opened window or door way, the rest of that opening being temporarily closed for instance by a pad or the like. Any regular opening in the wall leading to a supply

duct for fresh air, for instance a ventilation hole, may be used for the same purpose.

The flame of combustion is preferably completely enclosed by a heat resisting casing for confining the hot gases into a limited space and causing them to rise upwards so that they become well mixed with a powerful downward flow of air from the circulating fan above or on the side of the heating appliance such as the stove 10 or an electric resistance.

Any kind of suitable burner may be employed operating with either low or high pressure, which may be supplied from a blower or a tank containing air under pressure. A convenient method 15 of causing the oil to flow into the burner is to use the air circulating fan for such purpose supplying a sufficient oil pressure in the container, in which the quantity of oil for a certain heating operation is kept, thus, causing the oil to leave 20 the container, which may conveniently be located beneath the heating stove. The entire apparatus may in this way consist of three principal parts, viz. the casing with the enclosed oil burner, an aircooled motor with the air circulating fan above 25 and the container for the oil supply beneath the casing. The apparatus may be provided with automatic, preferably aircooled, relays and instruments for controlling the temperature by acting upon the oil supply, the amount of air and 30 other factors.

The oil for instance may be entirely shut off by the influence of a pyrostat on an automatic shutting off valve or it may be decreased or increased according to the conditions in each case. The 35 amount of electric resistance may in the same way be automatically controlled, in case an electric source of heat is being employed instead of a fuel burning appliance. If required by the circumstances it is possible to provide the oil container with cooling means or with a heat insulating covering. This may be desirable when employing a temperature in the neighborhood of 100° C. for instance in cow stables and the like.

If desired the combustion gases when leaving 45 the burner zone may be caused to pass into a system of tubes exposed to the air flow from the circulating fan. Such tube system may even be brought out into the open air for disposing of undesirable gases but normally no such gases nor 50 soot will be produced in a well built and properly used apparatus for gasifying and oxidizing the liquid fuel, if such is used.

The oil or gas to be used as a fuel may be supplied also from an outside container by means of 55 a hose through a hole or a narrow opening in a doorway or the like but preferably the oil should be kept in a container close to the stove as described above. The appliance may, naturally, be made in three or more separate parts but it is 60 most convenient to combine all the parts into one single piece of apparatus in order to be conveniently transported and managed.

The method may be carried out in two different 65 alternatives, viz. either by a slow gentle heating during a prolonged time of operation or by a very rapid rate of heating during only a few hours. The slow heating is to be preferred when it is desirable to prevent an undesirable overheating of furniture having delicate polished surfaces. Rapid heating may be desirable in localities such as cow stables, barracks, warehouses, etc.

In many cases it may be possible to use the 70 regular steam heat of an apartment for supplying a certain amount of the heat up to a certain temperature, the extra heating required being

employed for increasing it up to the desired limit. The method comprises, furthermore the use of smaller heating appliances adapted to be carried around by hand for injecting hot air into crevices, narrow places, holes, etc., where the vermin may be present, especially down at the floor line around the walls, inside of small closets and wardrobes, etc. Such appliances may be equipped with a source of heating in the shape of an enclosed flame, which is deviated by a current 10 of air from an electric motor fan. It is possible also to inject water or steam into the locality in order to influence the conditions of the air by controlling the humidity as desired. Certain gases, detrimental to the insects, may also be injected 15 together with the heated gases or separately.

For the sake of increasing the safety a container filled with a fire extinguishing matter, for instance CO₂, may be provided near the heating apparatus and caused to operate for instance by 20 means of a low temperature fuse opening a valve, if the temperature exceeds a permissible limit.

To protect sensitive surfaces and objects heat insulating covers may be applied if high temperatures would cause damage to such objects. 25

I claim:

1. A method of killing insects and micro-organisms in a substantially closed space which comprises introducing hot non-poisonous gases substantially composed of a mixture of CO₂, H₂O, 30 and air, creating a blast of said gases, initially and continually directing said gas downwardly while the gas is at its highest temperature, and causing circulation thereof until the entire space is substantially uniformly filled with said gas at 35 lethal temperature.

2. A method of killing insects and microorganisms in a substantially closed space as defined in claim 1 in which the hot non-poisonous gases are generated within the closed space by 40 combustion therein of a fluid fuel.

3. A method of killing insects and micro-organisms in a substantially closed space as defined in claim 1 in which the hot non-poisonous gases are generated within the closed space by 45 the combustion therein of a fluid fuel with air delivered as such to the zone of combustion of said fuel from outside said closed space.

4. A method of killing insects and micro-organisms in a substantially closed space which 50 comprises generating hot non-poisonous gaseous products of combustion therein by burning a liqued fuel with air delivered as such to the zone of combustion of said fuel from a point outside said space, creating a downwardly directed blast 55 of the atmosphere within said space adjacent the zone of combustion of the fuel whereby said blast mingles with the hot products of combustion and the mixture flows first toward the bottom of said space impinging against the bottom thereof and 60 then circulates within said space, and continuing said blast and the circulation of said mixture until the whole of said space is substantially uniformly heated to a temperature sufficient to kill said insects and microorganisms. 65

5. Method of killing insects and microorganisms in a substantially closed space as defined in claim 4 in which said combustion zone is supplied with fuel from a body thereof maintained in said space and in which said body of liquid fuel is 70 maintained at a temperature below that attained in said closed space by heat exchange with the air delivered to the combustion zone.
